UNITED STATES PATENT OFFICE.

OTTO KUNTZEN, OF BERLIN, GERMANY.

FARE-INDICATOR.

SPECIFICATION forming part of Letters Patent No. 673,401, dated May 7, 1901.

Application filed March 31, 1900. Serial No. 10,975. (No model.)

To all whom it may concern:

Be it known that I, OTTO KUNTZEN, a subject of the King of Prussia, Emperor of Germany, residing at Berlin, Germany, have invented certain new and useful Improvements in Fare-Indicators; and I do hereby declare the following to be a full, clear, and exact description of the invention, such as will enable others skilled in the art to which it appertains to make and use the same.

My invention relates more particularly to that class of fare-indicators which are adapted to be used on public carriages and cabs and other public conveyances and in which there is provided an indicator for the rate of fare to be paid, and there is also provided an indicator, usually in the form of a movable flag, to show whether the conveyance is engaged or disengaged.

The main object of my invention is to so construct an indicator of this character as to lessen the liability to mistakes and prevent other intentional or unintentional wrong handling or operation of the device. This object I attain by combining with the indicating-flag and the rate-indicating devices means connecting the latter with the flag, so that the flag will be automatically moved out of position to show that the carriage is engaged when the rate-indicating devices are set in operation and the flag will be restored to the "designating" position when the rate indications are moved out of service or position.

In the accompanying drawings I have illustrated a form of fare-indicator embodying my invention.

Figure 1 is a face view of the indicator with the flag lowered to indicate that the apparatus is in use and that the carriage is "engaged." Fig. 2 is a similar view showing the indicating apparatus as out of service and with the flag in the elevated position to show that the carriage is "disengaged." Fig. 3 is a plan view corresponding with Fig. 1. Fig. 4 is a sectional view on the line xx , Fig. 1, drawn to an enlarged scale. Fig. 5 is a face view of the mechanism shown in Fig. 4, the cover-plate being removed. Fig. 6 is a sectional view on the line zz , Figs. 4 and 5. Fig. 7 is a view showing the flag-bearing portion of the mechanism. Figs. 7^a and 7^b are views of detached parts illustrating the detents or check

paws for the flag-carrying sector, and Fig. 8 is a diagram illustrating various announcements on the announcement-drum.

The casing 44 of the indicator is of any suitable shape and has in its front suitable openings a and a' , Figs. 1 and 2, through which may show the rate and other such indications on a moving part, which in this instance is shown as in the form of a rotary drum 8, Figs. 5, 6, and 8, with five indications, including the "Rate I," "Rate II," "Rate III," "Pay," and "Out of service." This drum 8 turns in suitable bearings within the casing and can be rotated from the shaft 2 through a suitable intermittent self-locking feed-motion, the shaft 2 being provided with a suitable crank-handle 1 outside the casing. On this hand-crank shaft 2 are mounted a notched disk 3 and an arm 5 with a bent end, which at each revolution of the crank may engage with one of a series of radial slots in a disk 6, Figs. 4, 5, and 6, to thereby give to this disk a partial rotation, (one-fifth of a revolution in the case illustrated.) Between the radial slots the disk is made with concave edges, into which fits the edge of the main body of the disk 3, thus locking the disk 6 between its successive feed motions in a manner well understood.

The rotary disk 6 is coupled by a pin 7 or otherwise, Figs. 4 and 5, with a rotating announcement-drum 8. To the other side of the intermittent feed-disk 6 is secured, so as to rotate therewith, a lifting cam or cam-disk 13, Figs. 4 and 5, hereinafter referred to.

The indication-flag 23, which carries the sign "Disengaged" or other suitable indication, is carried by an arm 22 on a short shaft 21, which turns in a suitable bearing in the rear wall 42 of the casing, Fig. 6. Within the casing this same shaft 21 has affixed to it a sector 20, Figs. 6 and 7. This sector carries a segmental gear 19, (in this case a bevelled gear,) with which meshes a bevel-pinion 18, normally free to revolve on a fixed pin 43 in the casing 44. On this same pin rotates a pinion 9, in gear with a gear-wheel 4, Figs. 5 and 6, which is fastened to and revolves with the hand-crank shaft 2. The pinion 9 can be moved endwise on the pin 43 to a short distance to throw it into and out of engagement with the pinion 18 through the medium

of a ratchet-tooth clutch 16 17, Figs. 5 and 6. Normally the pinion 9 is held out of engagement with the pinion 18 by a spring 41, which is carried by the case and enters an annular groove in the hub 10 of the pinion 9, Figs. 4 and 5. The two pinions 9 and 18 may be thrown into engagement by means of a lever 12, which is pivoted at 12' to the case and the rear end of which rests upon the lifting-cam 13, before referred to, while the forward end 11 of the lever is wedge-shaped, as shown in Fig. 6, and is forked to pass over the pin 43 back of the hub 10 of the pinion 9. When the lifting-cam 13 in rotating raises the rear end of the lever 12, the wedge-shaped forward end, Fig. 11, will push the pinion 9 forward into the clutched engagement with the pinion 18.

A pull-spring 24, Fig. 7, or other suitable means may be provided to act on the sector 20, which carries the flag 23, to tend to draw the sector upward to keep the flag in position, as represented in Figs. 2 and 7, the sector then resting against a stop 25 within the casing. When the slotted feed-disk 6 is so turned by means of the crank-handle 1, shaft 2, and arm 5 that the curved edge marked "I" of the disk 6 comes to bear against the curved edge of the locking-disk 3, the lever 12 will have been so acted on by the lifting-cam 13 as to depress the forward end 11 of the lever 12, and thereby cause the pinion 9 to be moved endwise into a clutched engagement with the beveled pinion 18, and the continued rotation of the crank-shaft 2 will, through the wheel 4 and pinions 9 18, cause the sector 20 to be turned in the direction of the arrow, Fig. 7, to depress the flag 23 to its lower position, to thereby indicate that the apparatus has been put into use or set in service.

In connection with the sector 20 I prefer to use a spring-actuated detent or locking-pawl 26, which when the sector is raised will engage with the under side of the projecting part 29 of the sector, Figs. 7 and 7^a, to lock the sector and flag in their elevated positions. To free this detent, I may provide on the rear end of the lever 12, Figs. 4 and 5, a pin 15, which as the rear end of the lever is elevated will act on the rear end of the detent-lever 26, Fig. 7^a, to push it out of engagement with the portion 29 of the sector 20, and this as soon as or before the clutch 16 17 becomes engaged through the action of this same lever 12.

In order to hold the sector 20 and flag 23 in the depressed position as long as may be necessary against the action of a spring 24, I provide a spring-actuated check-pawl 27, Figs. 7 and 7^b, and opposite this on the sector I form a series of ratchet-teeth 30, such that while the sector is being moved down in the direction of the arrow, Fig. 7, the engaging end of the pawl 27 will slide over the teeth 30, but this pawl will prevent a return movement of the sector and flag until the pawl 27

is again disengaged. This freeing of the sector from the detent 27 may be effected by an arm 32, pivoted at 33 to the casing, Figs. 4 and 5, and acted upon by a cam or lifting disk, such as that marked 34, Fig. 4, connected to and returning with the intermittent feed-disk 6. A pin 31, projecting laterally from the arm 32, will at the proper time act on the rear end of the detent-lever 27, Fig. 7^b, to disengage the forward end of the detent from the teeth 30. Both spring-actuated detents 26 and 27 may be mounted upon the same axis 28, Figs. 7^a and 7^b.

The cam or lifting disk 34 is so constructed and arranged with reference to the feed-disk 6 that the described liberation of the detent 27 and sector 20 and the flag 23 takes place when the disk 6 is turned to bring the concave recess IV into engagement with the periphery of the locking-disk 3. In this position the announcement-drum 8 has been so turned that the designation "Pay" shows through the corresponding opening in the front of the case 44. If now a further revolution is imparted to the crank-shaft 2 the concave edge V of the feed-disk 6 will be in engagement with the periphery of the locking-disk 3 and the drum 8 will have been so turned that the designation "Out of service" will show through the opening in the case.

In order to make it impossible to turn the announcement-disk back from the indication "Pay" to show "Rate III" or from the indication "Out of service" to the indication "Pay," I provide a suitable check-pawl device. As a matter of convenience the arm 32 may constitute the pawl and the corresponding ratchet-teeth may be formed on the disk 34. By this means the driver of the vehicle is compelled when he wishes to set the apparatus "Out of service" first to set it at "Pay," thereby calling on the passenger to pay. Then only can he move the drum forward to the "Out of service" position. While the driver cannot set the device back from "Rate I" to "Out of service," nor from "Pay" back to "Rate III," nor from "Out of service" back to "Pay," owing to the arm 32 acting as a check-pawl in engagement with the teeth on the disk 34, it should be understood that these teeth are not continuous around the periphery of the disk 34; but such a portion of the disk 34 is left plain that the driver can set the announcement-drum 8 back from "Rate III" to "Rate II" or to "Rate I." In this way he can during a trip change from one rate to another, as may be necessary.

In order to prevent the driver from holding the flag 23 in its lowered position, as shown in Fig. 1, with the intent to defraud, while he sets the device at "Pay" or "Out of service," I prefer to provide a detent or check-pawl 37, turning on a pin 36 in the casing. The upper end 35 of this detent-lever 37 is bent, as shown in Figs. 4 and 5 and indicated in Fig. 7, and lies in a curved slot 38 in the sector 20. With the opposite end

of this detent-lever 37 I provide coöperating ratchet-teeth, which for convenience are shown as placed on the lifting disk or cam 13. When the sector 20 is in its upper position, 5 (represented in Fig. 7,) the lower edge 40 of the slot 38 so bears against the end 35 of the lever 37 as to hold the opposite end of this lever 37 free from engagement with the teeth on the disk 13, as shown in Fig. 4. The ratchet-teeth on this disk 13 are arranged at 10 those parts of the periphery of this disk which are opposite the engaging end of the detent 37 when the announcement-drum is set at "Pay" or "Out of service." In this position 15 the flag 23 must be in its upper or elevated position, since the liberation of the flag 23 from its lower position is effected by means of the arm 32 acting upon the detent 37 when the apparatus is set at "Pay." Now if the 20 driver should desire to set the announcement-drum at "Pay" while he held the flag 23 in its lower position this hand rotation of the feed-disk 6 would be prevented by the 25 detent 37 then gearing with the ratchet-teeth of the disk 13 then opposite the end of the lever 37. In other words, the drum cannot then be turned until the flag 23 has returned to its lower position so that the edge 40 of the slot 38 will have acted on the upper end 35 of 30 the lever 37 to draw the lower end of that lever out of engagement with the teeth of the disk 13.

I claim as my invention—

1. In a fare-indicator, the combination of

an indicating-flag with rate-indicating devices and means connecting the latter with the flag, whereby the flag is automatically moved out of position when the rate-indicating devices are set in operation and automatically restored when the said rate indications 40 are set out of service.

2. In a fare-indicator, the combination of an indicating-flag having a toothed sector and a toothed wheel geared thereto with rate-indicating devices and operating means for the latter, a clutch connection between the said operating means and the said toothed wheel, and means for throwing said clutch connection into action when the aforesaid devices are operated to set the rate, substantially as described.

3. In a fare-indicator, the combination of an indicating-flag and means tending to keep it in the disengaged position with rate-indicating devices, means connecting the latter 55 with the flag to move the flag out of position when the rate-indicating devices are set in operation, a check-pawl to hold the flag out of position, and means to release the check-pawl for the restoration of the flag, when the rate 60 indications are moved out of service, substantially as described.

In testimony whereof I affix my signature in presence of two witnesses.

OTTO KUNTZEN.
